Milton W. Blatner, Flushing, and Abraham H. Sachson, Brooklyn, N. Y., assignors to The Krier Corporation, New York, N. Y., a corporation of New York

Application January 22, 1948, Serial No. 143,978

Term of patent 14 years

(Cl. D83—1)

To all whom it may concern:

Be it known that we, Milton W. Blatner and Abraham H. Sachson, both citizens of the United States of America, residing respectively in Flushing, in the county of Queens, and in Brooklyn, in the county of Kings, both in the State of New York, have invented a new, original, and ornamental Design for a Diathermy Electrode Unit or the like, of which the following is a specification, reference being had to the accompanying drawing, forming part thereof.

Figure 1 is a front perspective view, viewed from above, of a diathermy electrode unit or the like, showing our new design;

Figure 2 is a rear perspective view, viewed from above; and

Figure 3 is a rear elevational view, in fully extended position.

We claim:

The ornamental design for a diathermy electrode unit or the like, as shown.

MILTON W. BLATNER.
ABRAHAM H. SACHSON.
